UNITED STATES PATENT OFFICE.

WILLIAM C. HORN, OF ORANGE, NEW JERSEY, ASSIGNOR TO KOCH SONS & COMPANY, OF NEW YORK, N. Y.

DESIGN FOR AN ALBUM-LEAF.

SPECIFICATION forming part of Design No. 20,015, dated July 15, 1890.

Application filed March 31, 1890. Serial No. 346,112. Term of patent 7 years.

To all whom it may concern:

Be it known that I, WILLIAM C. HORN, a citizen of the United States, residing at Orange, in the county of Essex and State of New Jersey, have invented and produced a Design for Books or Albums, of which the following is a full, clear, and exact description, reference being had to the accompanying drawings, forming part hereof, in which—

10 Figure 1 represents two album-leaves as laid out flat, and Fig. 2 a section of the same.

The leading feature of this design is a half-shield shape for the top, bottom, and free edge of the leaf, the straight line being at the op-

posite edge. The top *a*, bottom *b*, and free *c* edge of the leaf are curved substantially as shown. An opening or outline is shown at *e*, as usual in photographic albums.

I claim—

In a design for a book, the design of the leaves, substantially as herein shown and described.

Signed by me this 27th day of March, 1890.

WILLIAM C. HORN.
